Primary Examiner — Darcey E Gottschalk*Assistant Examiner* — Bailey M Knotts(74) *Attorney, Agent, or Firm* — McNees Wallace & Nurick LLC(57) **CLAIM**

The ornamental design for a wall lamp, as shown and described.

DESCRIPTION

FIG. 1 is a front elevation view of the wall lamp, showing the design.

FIG. 2 is a top-front-left perspective view of the wall lamp of FIG. 1, showing the design; and,

FIG. 3 is a left-front perspective view of the wall lamp of FIG. 1, showing the design.

Features shown on reflective surfaces are not part of the claimed design.

The area depicted in halftone within the broken line boundary in FIG. 3 depicts a portion (specifically the light bulb) of the wall lamp that forms no part of the claimed design.

1 Claim, 3 Drawing Sheets(56)
